UNITED STATES PATENT OFFICE

ALVEN E. WOLCOTT, OF LONG BEACH, CALIFORNIA

SILENT TOUCH TYPE OF COMBINATION LOCK

Application filed August 5, 1929. Serial No. 383,616.

My invention pertains to a combination lock which is especially adapted as a door lock and in the design illustrated is shown as for an enclosed automobile lock.

8 A feature of my invention is that the lock operates without necessitating a visible dial and the combination can be located thus without watching the movement of a dial and also without listening to the clicks in counting numbers. The lock works on the silent principle and the numbers of the combination are located by the sense of touch. I utilize an enumerator however, in which the only indication of the counting of the numbers to obtain the combination is by the sense of touch when operating an operating knob or the like.

20 A further object of my invention is having a lock in which when the door is locked the door handle may be turned in either direction without meeting a resistance and therefore overcomes the objections to locks in which the door handle has a limited movement and when such limit is reached the handle may be twisted forcibly by using tools and thus destroying the lock. With 25 my lock a thief in finding the handle continuously turning when the door is locked, gives up the attempt of trying to destroy the connection with the handle.

30 Another object of my invention is having the operating knob for counting the numbers of the combination and rotating the tumblers, free to turn in either direction at any time, whether the lock is locked or unlocked. This therefore overcomes the objection of a thief turning the knob which meets a resistance and then forcibly operating the knob until part of the lock is destroyed.

40 A further object of my invention is a combination lock in which a strong and cylindrical housing is utilized and connected to the panel of the door and in this rotates the stem of the handle. This stem extends preferably from front to back of the door and such stem forms a support and a journal for the rotating tumblers. These tumblers may be of any desired number, thus

giving a combination of from one count to any desired number.

Another object of my invention is having a zero latch, this being a means of locating a zero or starting point where the counting of the combination begins, this being done by pressing the knob inwardly and rotating the knob in either direction and when the zero point is reached the knob is automatically thrust outwardly slightly, at the same time a click indicates the zero. In the particular lock which I illustrate it is preferable to turn the knob in a clockwise direction as this places the tumblers in the proper position for beginning the counting of the combination.

55 Another detailed object of my invention is placing the operating knob locating the combination on the stem of the handle so that it is only necessary to use one hand to grasp the handle and to operate the knob. From the fact that it is not necessary to observe the movement of the knob or dial, nor necessary to listen to clicks or other sounds, my lock can be operated in the dark 60 or also by deaf and blind people and in places where it is extremely noisy where it would be difficult to detect the clicking sound of a lock operating on the sound principle. This also prevents bystanders 65 from counting the combination when a person unlocks the lock.

70 Another detail feature and advantage of my lock is that an authorized person in locking the lock may give the knob a partial turn, remembering how many counts in which direction he rotated the knob and then by rotating the knob in the opposite direction the same number of counts the lock may be unlocked. By this system the lock may be completely unlocked in about 75 two seconds and if tumblers are in the position locking the lock for a three tumbler lock the complete unlocking may be readily 80 done in about 5 or 6 seconds.

85 My invention is illustrated in the accompanying drawings, in which,

90 Figure 1 may be considered a horizontal section through a door and through the 95 100

housing of my lock, illustrating certain interior parts in plan;

Fig. 2 is a vertical longitudinal section of Fig. 1, with the knob and sleeve partly rotated and with the lock in the locked position;

Fig. 3 is a section similar to Fig. 2, with the lock in the position for unlocking and with the knob and sleeve partly rotated to illustrate the latching and enumerating levers;

Fig. 4 is a section similar to Fig. 2 with the latch lever in the latched position as when seeking for the zero or initial point of counting and with the lock in the locked position;

Fig. 5 is a vertical transverse section showing principally the bolt shifting means, certain of the parts being broken away;

Fig. 6 is a transverse section on the line 6—6 of Fig. 4, taken in the direction of the arrows, showing part of the detent attached to the lock lever, showing the position when the lock is locked;

Fig. 7 is a section similar to Fig. 6, showing the detent lever riding on the tumblers in the position for unlocking the lock;

Fig. 8 is a transverse section on the line 8—8 of Fig. 4 in the direction of the arrows, illustrating the latching and enumerating levers in section;

Fig. 9 is a perspective view of the housing taken from the inside of the lock;

Fig. 10 is a perspective view of the handle and handle stem taken from the inside of the lock;

Fig. 11 is a perspective view of the operating knob and the sleeve attached thereto, taken from the inside;

Fig. 12 is a perspective view of a collar riding on the handle stem and inside of the sleeve and fitting partly in the sleeve, taken from the inside;

Fig. 13 is a perspective view of the master or No. 1 tumbler taken from the inside of the lock;

Figs. 14 and 15 are perspective views respectively of the second and third tumblers;

Fig. 16 is a horizontal section through the lock above the operating parts thereof.

Referring first to the general construction, the front panel of a door is indicated by the numeral 11 and this has a reinforcing backing member 12, presuming the lock is fitted in a metal door such as an automobile door. The backing plate of the lock is indicated by the numeral 13. This plate and panel 13 and 11 are only illustrated by the parts adjacent the lock. The housing is designated generally by the numeral 14. This has a large interior bore 15 extending from the outer end inwardly, a succeeding smaller bore 16, there being an annular shoulder 17 between these bores and the small end bore 18; there being a relatively

large annular shoulder 19 between the bores 16 and 18 and in the shoulder 19 there is a transverse recess 20 for a locking pin hereunder detailed. Through the top of the housing there is a large, preferably rectangular opening 21, through which extends the detent attached to the locking lever as hereunder detailed. The housing on the outer end has preferably a curved head 22 with a reduced neck 23. The neck fits in an opening 24 which is preferably circular in the outer panel 11 and the backing plate 12. A pin or other securing means 25 is indicated as being connected to the housing on the outside and engaging in a small slot 26 in the panel 11 and backing piece 12.

A U-shaped locking piece 27 fits in an annular groove 28 in the outside of the housing. This has a certain spring tension and fits snugly against the backing member 12. This construction holds the housing from rotary and longitudinal movement in the door. It is obvious that any other suitable type of construction may be adapted for this purpose, it being essential that the housing be attached to the door to be immovable either by rotary or longitudinal movement.

The handle assembly designated generally by the numeral 29 has a handle end 30 and a stem 31. The handle and stem are illustrated as of the L-type. The stem is provided with an inner cylindrical section 32 which rotates in the small inner bore 18 of the housing. It has a squared or other irregular section 33 at the inner end and preferably a threaded bore 34 from the extreme inner end. A cam 35 is fitted on the squared end of the stem. This cam has preferably an annular surface 36 which fits against the inner surface of the back plate 13 of the door and the cam has an annular projection 37 fitting in the circular opening 38 in this back panel. A cap screw 39 is threaded in the bore 34 of the stem. Such cap screw preferably has a circular head 40 which may have a screw driver kerf or this may be filed off leaving a smooth surface. The head of the cap screw engages the outside of the back plate 13 and retains the stem in place. The cam has a recess 41 in one side with a pin 42 bridging this recess. The purpose of this pin is hereunder detailed.

The stem of the handle has a cylindrical section 43 with an annular shoulder 44 between the cylindrical sections 32 and 43. There is a third larger cylindrical section 45 with a small shoulder 46 between the sections 43 and 45. An outer cylindrical section 47 has an annular shoulder 48 separating it from the annular section 45. The section 47 merges by a curved section 49 into the handle proper (note particularly Figs. 2, 3, 4 and 10). The operating knob with its sleeve construction is designated gener-

ally by the assembly number 50 (note Fig. 11).

This has an outer knurled operating knob 51 which knob has an elongated internal bore 52; this bore having a riding fit on the section 45 of the handle stem. There is a shallow enlarged bore 53 which fits over the section 47 of the stem, there being an annular shoulder 54 between the bores 52 and 53. The sleeve has an outer cylindrical section 55 which is adapted to have a rotary fit in the bore 15 of the housing 14. There is a shallow annular groove 56 connecting the sleeve proper with the knob which is purely ornamental. The sleeve also has a cylindrical section 57 of slightly decreased diameter so that it does not contact with the cylindrical bore 15 and there is a shallow annular groove 58 between the sections 55 and 57. The sleeve is also provided with two longitudinal slots 59 and 60 which extend from the inner end 61 partly towards the knob. In one of these slots there is an enumerator lever 62 which is mounted on a pivot 63 bridging the slot 59. This enumerator lever has a nub 64 for a purpose hereunder detailed and is provided with a flattened inner surface 65 projecting beyond the nub. A rubber pin or small nub 66 is attached to each side of the enumerator lever and is adapted to prevent noise from this lever when contacting with the sides of the slot 59, and to hold the enumerator lever centrally spaced in the slot.

In the opposite side of the sleeve 50 and in the slot 60 there is a larger lever 67. This is mounted on a pivot pin 68 which bridges the inner end of the slot and this lever has a hook 69 extending from its inner end and on the inside towards the pintle. The enumerator lever and the large lever 62 and 67 respectively, are inwardly pressed by a semi-circular or C-shaped spring 70. This spring 45 is flat and fits in the annular groove 58 of the sleeve being attached to one of the levers by pins 71. Preferably the pins are mounted on the exterior of the levers and engage in perforations in the spring. This spring 50 exerts a considerable inward pressure, pressing both of the levers inwardly towards the stem.

The collar assembly designated generally by the numeral 72 (note Fig. 12), has an internal bore 73 forming a journal for the inner section 32 of the handle stem. This collar is held from rotation in the manner hereunder detailed. On the outer end of this collar there is a cylindrical enumerator ring 74 which has a series of notches 75 in its exterior surface. I find it of advantage to make this enumerator ring of a hard fibre or else of a soft metal so that the enumerator lever when engaging the notches 75 will not make a noise.

Formed integral with the collar there is an annular ring 76 against which the enumerator ring 74 abuts; the ring 74 being held from rotation by means of the pin 77 fitting into the ring 76. This ring 76 has an annular V-shaped groove 78 which is engaged by the hook 69 (note Fig. 4) and there is a lateral inclined notch 79 in the ring 76 leading to the peripheral surface 80 from the bottom of the annular groove 78.

The device for holding the collar 72 stationary in regard to the housing, employs a substantial collar 81 which has two pins 82 spaced apart. These pins fit against opposite sides of the rectangular opening 21 in the housing 14. This collar 81 has an annular recess 83 which engages the inner end 84 of the collar 72 and there is a pin 85 in the collar extending into an end notch 86 in the collar 72. Thus this collar when assembled in the housing is prevented from rotating and forms a part journal for the stem of the handle.

A washer 87 is fitted on the cylindrical portion 32 of the stem and has a transverse slot 88 therein through which extends a pin 89. This pin passes diametrically through the stem. The purpose of this washer is to hold the assembly of the tumblers on the collar 72 and at the same time retaining the collar 81 in a tight position against the end of the collar 72.

The tumblers have a No. 1 or master tumbler designated generally by the numeral 90 (see Fig. 13), which tumbler has an internal bore 91 bearing on the outside of the cylindrical section 92 of the collar 72 at the end adjacent the ring 76. This tumbler has an outer cylindrical section 93 which section has a longitudinal notch 94 forming the zero guide to begin the enumerating of the combination. A rubber pin 95 projects from one side of this section 93 and engages the enumerator lever 62 giving this a silent action when used to count the combination. The inner end of the No. 1 or master tumbler is provided with an annular flange 96, this having a cylindrical periphery 97. In this periphery there is a shallow or V-shaped notch 98 having rounded corners 99 joining the peripheral surface, this being for the purpose hereunder detailed and between the flange 96 and the outer cylindrical section 93 there is a reduced neck 100.

A driving pin 101 extends outwardly from the cylindrical surface 93 of the No. 1 or master tumbler and engages in the longitudinal notch 102 extending inwardly from the end 61 of the sleeve 50 having the operating knob thereon. By this means the rotation of the knob rotates the master tumbler. A coiled compression spring 103 is coiled on the cylindrical section 43 on the handle stem and thrusts against the enumerator ring 74 on the outside and against a

washer 104 which bears against an annular internal shoulder 105 on the sleeve 50 immediately inside of the knurled knob 51. This washer 104 when thrust outwardly by 5 the spring 103 has a slight clearance from the shoulder 46 of the handle stem and the washer is thrust inwardly when the knurled knob 51 is thrust inwardly to the position shown in Fig. 4, for a purpose hereunder 10 detailed.

The No. 1 or master tumbler has a hole 106 in the side of the flange 96 in which may be placed the driven pin 107, which pin is used to drive the second tumbler which is 15 designated generally by the numeral 108. (Note Fig. 14.) This tumbler has an inner bore 109 which is journaled on the cylindrical surface 92 of the collar 72 and is spaced from the flange 62 of the master tumbler by 20 a spacing washer 110. This tumbler has a cylindrical peripheral surface 111 with a longitudinal notch 112 therein. It is provided with a series of perforations 113 through the sides of the ring-like tumbler 25 and projecting from one side there are driven pins 114 driven by the driver 107 of the master tumbler and on the opposite side preferably a single driver pin 115 which operates on the third tumbler.

30 The third tumbler designated generally by the numeral 116 has an inner cylindrical surface 117 rotatable on the cylindrical surface 92 of the collar 72 adjacent its inner end and spaced from the second tumbler by a washer 35 118. This third tumbler has a cylindrical peripheral surface 119 with a longitudinal notch 120 therein. It is provided with a series of perforations 121 through the ring-like tumbler and in these perforations there 40 may be one or more driven pins 122.

The cam 35 is provided with a cam notch 123 (note Fig. 5), which is engaged by a 45 slidable cam latch 124 having a V-shaped end 125. This end is slidable in a guide bracket 126 which is mounted on the back plate 13 of the lock. A compression spring 127 coiled on a stem 128 of the cam latch, bears against the head 124 and a guide bracket 129; thus giving this cam latch a 50 sliding movement. Said latch is readily depressed out of the cam notch on rotation of the handle and its stem.

A trigger type of link 130 is pivotally mounted on the bolt lever 131, this lever being pivotally mounted on a pintle 132 which is secured to the back plate of the lock; the connection between the trigger and the bolt lever being by the pivot pin 133. The lower end of the bolt lever has a notch 134 which 55 engages a pin 135 on the door bolt 136. This bolt slides through a guide 137 and has an operative latch end 138. A spring 139 engaging the pin 140 on the bolt and attached to a bracket 141 on the back plate of the lock, 60 normally urges the bolt into its locking posi- 65

tion. The limit of travel of the bolt is regulated by the nubs 142 engaging the guide 137 and by the nub 143 engaging the inner end plate 144 of the lock.

The lock trigger 130 is urged downwardly by a tension spring 145 attached to the trigger and also to a fixed eye 146 preferably on the bolt guide. The trigger has a cut-out end 147 with an abutment face 148 to engage the pin 42 on the cam. The tip 149 of this trigger when in its downward position strikes a rubber cushion pin 150 which is attached preferably to the rear or inner plate of the lock.

The controlling detent 151 (note particularly Figs. 2, 3, 4, 6 and 7), is fixedly secured to a shaft 152. This shaft is journaled in a bracket 153 on the edge plate 154 of the lock and in its forward end is journaled in a hole in the backing plate 12. This 80 detent has a lower edge 155 which rides on the cylindrical surface of the three tumblers and is adapted to fit in the notches 98 of the master tumbler, 112 of the second tumbler, 120 of the third tumbler, when the tumblers are in position to allow unlocking and to lock. A curved arm 156 is rigidly attached to the inner end of the rock shaft 152; this curving around the cam 35 and there is an 85 angular end piece 157 which extends underneath the trigger link 130. When the detent 151 is riding on the peripheral surface of anyone of the tumblers the trigger 130 is held in a raised position, this being illustrated in full lines in Fig. 5. When however, the tumblers are in a position to allow the detent to fit in the three notches in the tumblers above mentioned, the rock shaft 152 is rocked so as to lower the arm 156, allowing the trigger to be pulled downwardly by the tension spring 145, bringing the abutment face 148 into position to be engaged by the pin 42 on the cam 35. Therefore when the handle is rotated in a clockwise direction in the present illustration, the trigger link 130 is given a movement to the right (having reference to Fig. 5). This 90 swings the bolt lever 131 in an anti-clockwise direction and retracting the bolt 136 with its latch end 138, thus unlocking the 95 door.

The general operation of the combination features of the lock is substantially as follows:

It will be noted that when the door is 100 locked and the trigger 130 is elevated in the position shown in Fig. 5, on the rotation of the handle and its stem in rotating the cam 35 that the pin 42 has a clearance from the trigger 130. Therefore the handle and its 105 stem can be rotated in either direction as far as desired and meet no resistance whatever. Therefore a thief, when the door is locked, cannot bring the handle and stem into a position where it meets resistance and 110

130

then by exerting superior force destroy the lock. This is one of the main features of my invention.

The procedure in locating the zero point for counting the combination, presuming the door is locked, is as follows:

In this case the lower edge 155 of the detent 151 is riding on the peripheral surface of one or more of the cylindrical tumblers and normally the knurled knob 51 with its sleeve 50 is thrust to its outermost position as shown in Figs. 1, 2 and 3. The operator in opening the lock thrusts the knurled knob and the sleeve inwardly against the compression of the spring 103. This carries the latch 67 from the position shown in Fig. 3 in which it is riding on the peripheral surface 80 of the ring 76, on the collar 72 to the position illustrated in Fig. 4, in which it is pressed into the longitudinal notch 94 of the No. 1 or master tumbler; this master tumbler and the sleeve rotating together in the manner above described, by means of the pin 101 on the master tumbler engaging in the end notch 102 on the sleeve. This action allows the hook 69 of the latch 67 to fit in the annular groove 78 of the ring 76 of the collar 72. Rotating the knob then brings the latch 67 so that the inner or hook end 69 releases at the sloping groove or notch 79 in the ring 76. This allows the spring 103 to thrust the knurled knob outwardly and the action gives a slight click or noise. This indicates that the combination features are in the zero position to start the enumeration in unlocking the lock.

In the unlocking position there is a slight clearance or tolerance between the shoulder 54 of the knob and the shoulder 48 of the handle stem so that in rotating the knob and its sleeve there is no frictional resistance to its rotation except the bearing resistance. Presuming the combination requires first a rotation in a clockwise direction, in this position the enumerator lever 62 has its nub 64 riding on the peripheral surface of the enumerator ring 74 and in turning the knob a slight hesitation is felt when the nub drops into each of the notches 75. This is a silent action and it gives no click whatever and there is nothing visible to indicate this action. The desired count causes the master tumbler which rotates with the sleeve to rotate on the stationary collar 72 until its driving pin engages one of the driven pins on the No. 2 tumbler. This rotating action of the knob causes a rotation of the second tumbler and then the third tumbler through the medium of the driving and driven pins and the No. 3 tumbler is shifted to location by making the proper counts of the hesitations felt by the action of the enumerating lever on the enumerator ring. Then the knob may be rotated in the opposite direction the desired

number of counts until the No. 2 tumbler is brought into location and finally the master tumbler is brought into location. When the tumblers are in location the three notches 98, 112 and 120 are in alignment and are directly below the opening 21 in the housing 14, allowing the detent to drop and to lower the trigger 130, allowing opening of the door in the usual way by rotating the handle. The notch 98 of the master tumbler has the sloping sides 99 to enable it in locking the lock to raise the detent by turning the knurled knob.

An important feature of my invention is that when the lock is locked so that the bolt is immovable, the handle and stem can be rotated in either direction and will not meet a positive resistance. The V-shaped resiliently mounted cam latch engaging in the notch in the cam 35 does not give a positive resistance to the rotation of the cam and stem, but functions to center the handle and stem in proper position so that the pin 42 will engage the trigger link to shift the bolt in the unlocking operation. Therefore when the door is closed and locked, a thief cannot turn the handle until it meets a positive resistance and then by using additional force, such as a hammer on the handle or using a pipe as a lever, use force to break a part of the lock. Also the knurled knob 50 may be rotated in either direction, whether the lock is in the locked or unlocked position. This knob is freely movable and therefore a thief cannot jam this into a position having a resistance and exert force to destroy part of the lock.

It is quite obvious that in enumerating the proper combination it is not necessary for a person to observe the knob and the movement thereof as in the first place they can locate the zero or starting position by thrusting the knob inwardly and turning it until it is thrust outwardly by the spring 103. This action is readily observed by the sense of touch and if desired the device may give a slight click or noise in locating the zero or starting position. In shifting the tumblers there is no sound emitted by the enumerator lever engaging in the notches in the enumerator ring, but there is a slight hesitating movement or slight resistance developed which indicates clearly to the operator the various counts to be made in obtaining this combination.

Another feature of my invention is that the tumblers rotate around the stem of the handle, there being a fixed sleeve between the tumblers and this stem and when everything is in position to shift the bolt, the rotation of the handle and stem cannot affect the tumblers.

Various changes may be made in the principles of my invention without depart-

ing from the spirit thereof as set forth in the description, drawings and claims.

I claim:

1. A combination lock having a movable handle and a combination locating device independent of the handle, the handle and the locating device being adapted to be positioned on the outside of a door, the locating device being slidable longitudinally and 10 rotatable with means cooperating therewith to indicate the zero point for starting the enumeration of the combination, and means cooperating with the locating device to shift such device to its original position of longitudinal movement prior to enumerating the combination and means to limit the movement of the handle to a rotational movement.

2. A combination lock having a handle 20 with a stem, a combination locking device having a knob-like structure rotatably mounted on the stem, the knob and the handle being adapted for positioning on the outside of a door, the knob being slidable 25 longitudinally of the stem, means to retain the knob in the position of longitudinal movement, means cooperating with the knob in the rotation to release the knob, means to return the knob to its initial position relative to the stem before the longitudinal movement, such action indicating a zero or starting position in enumerating the combination, means cooperating with the knob in the rotation thereof to enumerate the 35 numbers of the combination by the sense of touch or feel, independent of visual observation or by sound, a bolt connected with the lock, means operated by the stem when the combination is in the unlocking position, 40 to shift the bolt by the rotation of the stem, said means being shiftable when the combination is in the locked position, to allow rotation of the handle and stem in either direction without meeting a positive resistance.

3. A combination lock having a handle and a stem connected thereto, a combination locating device, the handle and the locating device being adapted for positioning on the 50 outside of a door, one or more tumblers operated by the combination locating device, a detent engaging said tumbler or tumblers to be retained in the locking or unlocking position, an interconnecting means 55 between the stem and the bolt to shift the bolt, an interconnecting device between the detent and the said means to shift the said means to prevent operation of the bolt by the stem when the detent is in the locking 60 position, the positioning of such device and the said interconnecting means being adapted to permit rotation of the handle and the stem in either direction without meeting positive resistance when the detent 65 is in the locking position.

4. A combination lock having a handle with a stem, the lock having a front and a rear plate, a fixed housing secured to one of the plates, a rotatable sleeve in the housing having a knob extending on the outside of the front plate of the lock, the stem being journaled in the said knob, the said stem also having a journal in the back plate of the lock, a stationary collar surrounding the stem, one or more ring-like rotatable tumblers on the collar, and an interconnecting means between the knob, the sleeve and the tumbler or tumblers to move said tumbler or tumblers to a position for unlocking the lock, a bolt for the lock and means operated by the stem to shift the bolt into its unlocked position when the tumbler or tumblers are in a position to allow such unlocking.

5. A combination lock as claimed in claim 4, the housing having an opening with a detent extending therethrough engaging the tumbler or tumblers, said detent in the locked position of the lock riding on one or more of the tumbler or tumblers and in the unlocked position resting in a transverse groove or notch in the tumbler or tumblers, and an interconnecting device between the detent and the connection between the stem and the bolt, to shift said connecting means.

6. A combination lock having a handle with a stem, a combination rotatable locating knob, the knob and the handle being adapted for mounting on the outside of a door, the knob being rotatable in either direction, without meeting a positive resistance whether the lock is locked or unlocked, said knob being shiftable in an axial direction and rotatable to indicate a zero or starting point for enumerating the combination, and means to return the knob to its original position at such zero or starting position, such zero locating operation being independent of visible observation or of sound, and means operated by the stem to unlock the bolt of the lock.

7. A combination lock having a rotatable handle and stem, a cam connected to the stem, a slideable cam latch to engage said cam and to position the stem, a slideable bolt and means interconnecting the cam and the bolt to shift the bolt to the unlocking position, the said cam latch and cam positioning part of said means in position to interconnect with the means to shift the bolt.

8. A lock having a handle with a stem connected thereto, said handle and stem being rotatable, a locking bolt, a combination of locking and unlocking devices, means interconnecting said devices, the stem, and the bolt for locating the bolt in the locked or unlocked position, and means permitting the free rotation of the handle and stem in either direction any number of times without meeting a positive resistance when the

130

bolt is in the locked position and when the locking and unlocking devices are in any operative position they may assume when the bolt is locked except the position for 5 retracting the bolt.

9. A lock having in combination a handle with a stem, the handle and stem being rotatable as a unit, a bolt, a trigger device for shifting the bolt to unlocked position only, 10 means for interconnecting the stem and the trigger to shift the bolt, means to shift the trigger out of the engaging position when the bolt is in the locked position permitting free rotation of the handle and the stem in 15 either direction any number of times without meeting a positive resistance.

10. A lock as claimed in claim 9, the lock having a combination of locking and unlocking devices cooperating with the stem, and 20 a single knob rotatable on the stem for positioning said locking and unlocking devices in the proper position for locking or unlocking of the said bolt.

11. A lock having a rotatable handle, 25 means to prevent longitudinal sliding of the handle, a locking bolt, an interconnecting means between the handle and the bolt to shift the bolt into unlocking position by rotation of the handle, means to render said 30 interconnection inoperative when the bolt is in the locked position whereby the handle may be freely rotatable in either direction without meeting a positive resistance and means independent of the operation of the 35 handle to shift the bolt to locking position, a combination of rotatable locking and unlocking devices forming part of the interconnecting means, a rotatable knob for determining a combination and for operating 40 said devices, said knob being freely rotatable in either direction without meeting a positive resistance whether the bolt is in the locked or unlocked position.

12. A lock having a rotatable handle, a 45 locking bolt, a combination of locking and unlocking devices forming an interconnection between the handle and the bolt, a rotatable knob to operate said devices, a bolt actuating means operative by the handle, 50 an interconnecting means between said devices and the bolt actuating means to render said latter means inoperative when the bolt is in the locked position whereby the handle may be rotatable in either direction without 55 meeting a positive resistance, and the said knob also being rotatable in either direction without meeting a positive resistance whether the bolt is locked or unlocked.

13. A lock as claimed in claim 12, the 60 said knob being shiftable longitudinally to indicate a zero position of the combination of the said devices and in its rotation indicating by sense of touch without observation or sound the desired positioning of the 65 said devices.

14. A lock having a combination of locking and unlocking devices, a single rotatable knob for operating said devices, means to ascertain a zero or starting position in the rotation of such knob, and means to 70 indicate by the sense of touch without observation or sound the desired rotation of the knob in either direction to locate said devices in a desired position for unlocking the lock, and a handle independent of the 75 knob to unlock the lock, means independent of the action of the operator and operable at the zero position to shift the knob in a manner to indicate the zero or starting point.

15. A lock having in combination a tubular, fixed housing, a rotatable operating sleeve having a knob rotatable in said housing, a collar in the sleeve with means to secure said collar stationary as regards the housing, a handle having a stem extending through the knob, the collar, the sleeve, and the housing, a combination of locking and unlocking devices having parts thereof rotatably mounted on the said collar and actuated by the rotation of the knob and the 80 sleeve, a locking bolt operated by the stem with means to interconnect the bolt and the stem through the medium of said devices for shifting the bolt to the locked and unlocked position. 95

In testimony whereof I have signed my name to this specification.

ALVEN E. WOLCOTT.
